BY Dolan Polack ATTORNEY

UNITED STATES PATENT OFFICE

JAMES W. MOORE, OF WEST NEW YORK, NEW JERSEY

PROTECTION BOOTH

Application filed May 20, 1931. Serial No. 538,734.

This invention relates to new and useful improvements in a protection booth, to protect banks and other institutions handling valuable instruments over the counter.

5 The invention has for an object the construction of a protection booth which is for use in a bank or the like and adapted to house a person acting as a sentinel. It is proposed to construct the booth of bullet-proof material.

A still further object of this invention is the provision of a means for hearing conversations between persons in the cages behind the counter and customers, by the person within the booth, so that in the event of a holdup the sentinel will know about it.

A still further object of this invention is the provision of a phone operable by the person within the booth for the purpose of notifying the police regarding the holdup.

A still further object of the invention is the provision of a means for automatically closing the doors of the bank to entrap the holdup men.

25 Another one of the objects of this invention is the provision of apertures in the bullet-proof booth, the provision of transparent windows, and means for simultaneously closing the apertures and covering the windows with bullet-proof material in the event of an emergency.

Another one of the objects of this invention is the provision of means within the booth for the comfort of the sentinel, such as 35 a chair, table and the like.

A still further object of the invention is the construction of a booth of the class mentioned which is of simple durable construction, dependable in use and efficient in action, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming 50 a material part of this disclosure:

Fig. 1 is a fragmentary plan view of a portion of a bank with a protection booth according to this invention.

Fig. 2 is a vertical sectional view of the booth constructed according to this invention.

Fig. 3 is a fragmentary sectional view taken on the line 3-3 of Fig. 1 showing in particular the construction of the counter.

Fig. 4 is a fragmentary elevational view 80 of a portion of the bank showing the door, and a means for closing the door automatically.

Fig. 5 is a schematic wiring diagram for use in conjunction with the booth.

Fig. 6 is a fragmentary enlarged sectional view taken on the line 6-6 of Fig. 2 for the purpose of showing one of the controlling switches in detail.

Fig. 7 is a sectional view taken on the line 70 7-7 of Fig. 2.

Fig. 8 is a perspective view of a frame for supporting the protection booth upon a wall.

Fig. 9 is a view illustrating a method for 75 locking rotary doors which may be used in the bank, during an emergency.

Fig. 10 is a horizontal sectional view taken on the line 10-10 of Fig. 9 and showing 80 in particular details of the rotary door.

Fig. 11 is a view similar to a portion of Fig. 2 but illustrating a modification.

Fig. 12 is a fragmentary horizontal sectional view taken on the line 12-12 of 85 Fig. 11.

Fig. 13 is a fragment similar to a portion of Fig. 2 but illustrating a still further modification.

Fig. 14 is a fragmentary horizontal sec- 90 tional view taken on the line 14-14 of Fig. 13.

The protection booth is for location within a bank 10 which is provided with customer walking space 11. A counter 12 is arranged 95 upon the flooring and cages 13 for various cashiers are located behind the counter 12. In one corner of the bank the protection booth 14 is positioned, preferably at an elevation by reason of being supported upon 100

a post 15 so that the sentinel therein may view the entire bank at one time.

The protection booth comprises a bullet-proof container 16 shown of cylindrical form and having a substantially dome shaped top 17. The container has a flat bottom 18 which rests upon the top of the post 15. To gain access to the interior of the container, the base 18 is provided with an entrance opening 19 which is normally closed by a hinged cover 20. Numeral 21 indicates the hinge of the cover. A latch 22 operable from the inside of the container is provided for normally holding the cover in a closed position. A pivoted peep cover 23 is mounted upon the cover 20 for the purpose of looking through apertures 24 in the cover to see whether any enemy is hid below the container and would enter upon opening of the cover. A plurality of rungs 25 are arranged upon the post 15 to allow persons to climb up through the opening 19.

Within the container a seat 26 is located so that the person may sit in comfort therein. A table 27 is also mounted within the container. A phone 28 is shown resting upon the table and is for the purpose of calling the police in the event of an emergency. The container is formed with transparent windows 29 comprising thick sheets of glass engaged within openings in the sides of the container. A guard 30 is normally located beneath the window openings 29 and is adapted to be moved upwards so as to cover the window openings in time of emergency. A panel board 30' is mounted upon the table 27 and is provided with a plurality of switches 31 operating various circuits so that the person within the protection booth may control various elements. A specific list of these elements will not be given, since they may be any, such as controlling the lights and communication, etc. One of the switches indicated schematically in Fig. 5 by reference numeral 31 is used for automatically closing the bank doors. This is accomplished by the provision of a circuit 32 which includes a solenoid 33 having a core 34 connected with a pivoted door operating lever 35. This lever is mounted pivotally at 36 and its other end engages with a peg 37 projecting from the bottom of the bank door 38. Dot and dash lines 39 indicate the opened position of the lever in which the door is open.

Upon the counter 12 and located at various points thereon, there are situated a plurality of microphones 40. Preferably, one microphone should be provided for each cage 13. These microphones are located below the counter and directly communicate with the air above the counter by reason of openings 41 in the counter. Wire gauze 42 closes the openings so as to prevent articles from falling within the microphones. These microphones are connected up in a circuit, as for

example illustrated in Fig. 5, with the earphones 43 located within the booth. These earphones in Fig. 2 are shown suspended by a hook 44 so that they may readily be removed and used by the sentinel. In lieu of the earphones a loud speaker can be provided so that at all times the sentinel may hear conversations going on at the various cages.

A plurality of apertures 45 are formed in the top of the dome shaped portion of the booth for the purpose of providing air. A dome shaped plate 46 is longitudinally supported upon a rivet 47 upon the inner side of the dome shaped top. This plate is formed with a plurality of apertures 48 capable of aligning with the apertures 45 in a certain position. Gear teeth 49 are formed along the periphery of the plate 46 and mesh with pinions 50 diametrically opposite each other. These pinions are supported by shafts 51 rotative within the booth. Worm pinions 52 are mounted upon the shafts 51 and mesh with rack teeth 53 upon the guard 30. The guard 30 is mounted so as to be longitudinally slidable but non-rotative by reason of a stud 54 projecting from the booth and engaging through a longitudinal aperture 55 in the guard. One of the shafts 51 connects with an electric motor 56. Pinions 60 are fixed upon the shafts 51 and connected by a chain drive 61 so that both of the shafts rotate in unison. The motor 56 is shunted across the solenoid 33 as clearly shown in Fig. 5. A switch 57 is located in the path of motion of the guard 30 and particularly opens when the guard is in its raised position. The switch has a projecting end in the path of motion of the top edge 58 of the guard 30 so that when the projecting end is lifted the circuit is broken.

The operation of the device may be traced by assuming a person within the booth. This person listens in on the earphones 43 and keeps watching through the windows 29. In the event of a holdup, the guard immediately closes switch 31, which causes the simultaneous closing of the doors of the bank, the lifting of the guard 30 so as to shield the windows and the rotating of the plate 46 so as to close the openings 45. When the openings 45 are closed, it is impossible for the person within the protection booth to be routed by reason of gas fumes such as from a tear bomb. The person then may call the police and set up a general alarm. In the event that the robbers are unaware that the guard is sending in the alarm, it is best that no noise be made in the bank such as the ringing of a gong so that the robbers will not be disturbed until the arrival of the police.

Closing of the switch 31 causes energization of the solenoid 33 which closes the bank door 38. The circuit is also closed, upon closing the switch 31, through the electric motor 56 which causes rotation of the shafts 51, the corresponding lifting of the guard 30, and

rotating of the plate 46. To leave the booth, it is necessary that the latch 22 be first opened and then the door 20. The person may climb down the rungs 25.

5 It is to be understood that my protection booth 14 may be made of any bullet proof metal, fibre or other composition and that it may also be used in railway trains and the like.

10 The protection booth is also supported upon the wall by a frame 65. This frame consists of a vertical member 66 for attachment upon the wall, and upper and lower encircling braces 67. The braces 67 are 15 shown to be of substantially squared form and adapted to engage around the upper and lower ends of the booth.

In Fig. 9, a means has been disclosed for holding a rotary door of the bank latched in 20 the event of an emergency. This means comprises a control lever 68 for location within the booth and pivotally mounted at its bottom end 69. A link 70 pivotally connects with the lever 68 and with a bell crank 25 71 which is pivotally supported intermediately at 72. The bell crank also connects with a sleeve 73 provided with a key 74 engaging with a stationary collar 75. The member 73 is slidably mounted so that a disc 30 76 at its bottom end may be lowered. The disc 76 is provided with pegs 77 capable of engaging within apertures 78 and revolving door 79 to latch the door. The door 79 is of the type having separate leaves which may 35 be collapsed relative to each other. Screws 80 engaged through the ends of the levers 81 which hold the sections of the door in the open condition so that collapsing is impossible. The intention is that the only way 40 to operate the door is to revolve it so that when it is held against revolving, persons cannot pass through.

In Fig. 11, another modification of the invention has been disclosed in which a means 45 is provided for preventing shooting through the glass windows 29. This means is in the form of shutters 82 which are pivotally mounted upon lugs 83 within the booth so that they may assume an inoperative position 50 as shown in full lines on the drawings, or a raised operative position as indicated by the dot and dash lines 84. These shutters are flat as shown in Fig. 12 and arranged upon chords of the booth. Further, the shutters 55 are made from metal which is capable of stopping a bullet. Catches 85 upon the inside of the booth are capable of coacting with the top edges of the shutters to hold the latter elements in their raised operative positions.

In Figs. 13 and 14, another modified arrangement of the device has been disclosed in which the booth 16 is provided with openings 29^a which are not restricted by glass. 60 Metallic, individual small shutters 86 are

slidably mounted within the booth and capable of normally closing portions of the opening. Each of these shutters has a tongue portion 87 on its top engaging within a guide element 88 attached within the booth. The shutters have inclined sides 89 terminating in flat tops 90 so that when a bullet strikes the inclined side it cannot pass upwards further than the top 90. The intention is that a guard within the booth can open any one of the shutters to shoot out at the burglars, and after the shot is fired, release the shutters whereupon they automatically close.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A protection booth for location in a bank, comprising a bullet-proof container having a plurality of apertures formed in its top and having window openings closed by transparent material, a disc movably mounted in the top of the booth and having apertures alignable with the apertures in the top of the booth for closing them in a certain position, a guard movably mounted within the booth for assuming a position behind the transparent windows, and a means for simultaneously moving the guard to its closed position and moving the disc to a position in which it closes the apertures in the booth.

2. A protection booth for location in a bank, comprising a bullet-proof container having a plurality of apertures formed in its top and having window openings closed by transparent material, a disc movably mounted in the top of the booth and having apertures alignable with the apertures in the top of the booth for closing them in a certain position, a guard movably mounted within the booth for assuming a position behind the transparent windows, and a means for simultaneously moving the guard to its closed position and moving the disc to a position in which it closes the apertures in the booth, said latter means including a circuit having a solenoid for automatically closing the door of the bank.

3. A protection booth for location in a bank, comprising a bullet-proof container having a plurality of apertures formed in its top and having window openings closed by transparent material, a disc movably mounted in the top of the booth and having apertures alignable with the apertures in the top of the booth for closing them in a certain position, a guard movably mounted within the booth for assuming a position behind

the transparent windows, and a means for simultaneously moving the guard to its closed position and moving the disc to a position in which it closes the apertures in the booth, 5 comprising shafts rotatively mounted within the booth, pinions fixed upon the shafts and engaging gear teeth formed on the periphery of the said disc, worm pinions fixed upon said shafts and engaging rack teeth 10 upon said guard, means for revolving one shaft and means for causing all the shafts to revolve in unison.

4. A protection booth for location in a bank, comprising a bullet-proof container 15 having a plurality of apertures formed in its top and having window openings closed by transparent material, a disc movably mounted in the top of the booth and having apertures alignable with the apertures in the top 20 of the booth for closing them in a certain position a guard movably mounted within the booth for assuming a position behind the transparent windows, and a means for simultaneously moving the guard to its closed position and moving the disc to a position in which it closes the apertures in the booth, 25 comprising shafts rotatively mounted within the booth, pinions fixed upon the shafts and engaging gear teeth formed on the periphery 30 of the said disc, worm pinions fixed upon

said shafts and engaging rack teeth upon said guard, means for revolving one shaft and means for causing all the shafts to revolve in unison, comprising pinions fixed upon the shafts, and a drive chain engaging the said 70 pinions.

5. A protection booth for location in a bank, comprising a bullet-proof container having a plurality of apertures formed in its top and having window openings closed by transparent material, a disc movably mounted in the top of the booth and having apertures alignable with the apertures in the top of the booth for closing them in a certain position, a guard movably mounted within the booth for assuming a position behind the transparent windows, and a means for simultaneously moving the guard to its closed position and moving the disc to a position in which it closes the apertures in the booth, comprising shafts rotatively mounted within the booth, means for transmitting rotations of the shafts to the disc, means for transmitting rotations of the shafts to the guard, means for revolving one of the shafts, and means for causing all of the shafts to revolve in unison.

In testimony whereof I have affixed my signature.

JAMES W. MOORE.
